(57) **CLAIM**

The ornamental design for the dual display camera, as shown and described.

DESCRIPTION

FIG. 1 is a front perspective view of the dual display camera; FIG. 2 is a rear perspective view of FIG. 1; FIG. 3 is a front elevational view of FIG. 1; FIG. 4 is a right side elevational view of FIG. 1; FIG. 5 is a rear elevational view of FIG. 1; FIG. 6 is a left side elevational view of FIG. 1; FIG. 7 is top elevational view of FIG. 1; and, FIG. 8 is a bottom elevational view of FIG. 1. The ornamental design that is claimed is shown in solid lines in the drawings. The portions of the dual display camera in broken lines are shown for illustrative purposes only and form no part of the claimed design.
